UNITED STATES PATENT OFFICE.

ALEXANDER H. HYNDMAN, OF CHICAGO, ILLINOIS.

MAGNETO.

1,403,689.

Specification of Letters Patent. Patented Jan. 17, 1922.

Application filed January 9, 1919. Serial No. 270,260.

To all whom it may concern:

Be it known that I, ALEXANDER H. HYNDMAN, a citizen of Canada, residing at Chicago, in the county of Cook, State of Illinois, have invented certain new and useful Improvements in Magnetos, of which the following is a specification.

The present invention relates generally to magnetos of the oscillating armature type and more particularly to magnetos of this type which are used with internal combustion engines to supply the electric current for exploding the fuel charges in the engine cylinders. The principal object of the invention is to produce a magneto of the kind specified which shall be efficient and durable in operation and at the same time economical to manufacture. Another object of the invention is to provide a novel construction which is readily adaptable to the production of either high or low tension machines. For a full understanding of my invention reference should be had to the following detailed description taken in connection with the accompanying drawing, while the scope of the invention will be set forth in the appended claims.

In the said drawing, Fig. 1 is a side elevation of a low tension magneto constructed in accordance with my invention; Fig. 2 is a front elevation of the same; Fig. 3 is a bottom plan view of the same; Fig. 4 is a diagram illustrating said magneto in association with an engine cylinder and showing particularly the electric circuit; Fig. 5 is a side elevation of a high tension magneto constructed in accordance with my invention; Fig. 6 is a front elevation of the same; Fig. 7 is a fragmentary view in side elevation illustrating the main armature and associated parts in depressed position; Fig. 8 is a bottom plan view of the high tension structure; and Fig. 9 is a diagram of the electrical circuits of the high tension machine. Throughout these views like characters refer to like parts.

Referring more particularly to the low tension machine, illustrated in Figs. 1 to 4 inclusive, 10 designates a permanent magnet which is preferably of horse-shoe shape. This magnet is secured to a suitable base 11 by a bolt 12 which passes through holes in said base and in a bar 13 which bridges the space between the arms of the magnet and bears against them at its outer ends. The nut 14 on the threaded end of

the bolt 12, when screwed down tightly against the bar 13, securely holds the parts in place, it being understood that the head of the bolt 12 engages the rear face of the 60 base 11. The magnet 10 is composed of steel or other suitable magnetic material while the base 11 and the bar 13 are composed of brass or other suitable non-magnetic material.

The armature 15 consists of a bar 16 upon which the tightly fitting blocks or sleeves 17 and 18 are firmly secured. These blocks are in position to engage the pole faces of the magnet 10 and together with 70 the intervening portion of the bar 16, complete the magnetic circuit between those poles. The bar 16 and the blocks 17 and 18 are composed of soft iron or other suitable magnetic material. The armature 15 75 is guided in its to and fro movements by guiding members 20 and 21 of brass or other non-magnetic material which are secured to the base 11 by any suitable means, as for example by screws, such as the screw 80 22 shown in connection with the guide 20. Each of these members 20 and 21 is in the form of a yoke with a central open portion, which provides space for the free movement of the bar 16. The depending 85 portions of the guide 21 and the adjacent end of the bar 16 are provided with holes for the passage of a pivot pin 23. About this pin as a center the armature 15 oscillates and it is guided in its oscillations by 90 the depending portions of the guide 20. It may be pointed out that the pin 23 need not be used but may be withdrawn from the structure and still the depending portions of the guide member 21 will suffice to hold that 95 end of the armature against displacement through all the to and fro movements of the opposite end. It will be observed that the magnetic flux through the armature and the adjacent pole pieces will tend to hold 100 the armature against displacement at this point. The opposite end of the bar 16 extends some distance beyond the magnet 10 and is to be positioned so as to be actuated by an oscillating member 24 which is given 105 its oscillatory movement by the engine or other mechanism with which the magneto is to be used. This member 24 should be arranged to give a quick sharp blow to the end of the bar 16 of the armature. Such a 110 blow will force the bar 16 downward between the depending guiding portions of the

member 20. Its return may be brought about wholly in response to the action of the magnet 10 or its return may be assisted by the use of a return compression spring 25 which acts between the under side of the bar 16 and the upper side of a yoke 26 which is secured to the bottom of the guide 20. Pins 27 and 28 upon the bar 16 and yoke 26 respectively may be used to guide the spring and keep it in place. If the return of the armature is to be brought about wholly by the magnetic attraction of the magnet 10 then the spring 25 and yoke 26 should be omitted.

15 An electric coil 29 is mounted upon that portion of the bar 16 which lies between the magnetic blocks 17 and 18. As indicated in the diagram of Fig. 4, one terminal of the coil 29 is grounded and the other is connected to an insulated terminal 30 which constitutes one of the sparking terminals in the cylinder 31 of an internal combustion engine. The other sparking terminal 32 is mounted upon a reciprocating rod 33 which may be actuated by the free end of the bar 16. As the latter moves downward the contact 32 is mechanically moved out of engagement with contact 30. As the free end of the armature bar 16 moves upward a spring 34 upon the rod 33 acting between the engine cylinder and the sleeve 35 on the rod 33 brings the contacts 30 and 32 into engagement. Ordinarily, the ground connection of the coil 29 is made by connecting one terminal of the coil to some portion of the structure which is grounded. In the present instance connection is made with the bar 16 and the latter is shown grounded at 36. In like manner the contact 32 is grounded by being electrically connected to the cylinder 31. The ground connection of the latter is indicated at 37. From these connections it will be seen that a circuit may be traced from ground 36 through a portion of bar 16, the windings of coil 29, conductor 38, contacts 30 and 32, and engine cylinder 31 to ground at 37. It may be pointed out that the contact 30 which extends through the cylinder head is provided 50 with suitable insulation shown at 39.

From this description it will be seen that when the free end of the armature bar 16 is given a quick hammer blow by the oscillating member 24, the magnetic circuit which is completed through the magnet 10, the blocks 17 and 18 and the intervening portion of bar 16, will be disturbed and the number of lines of force which normally pass through the coil 29 will be greatly lessened by reason 55 of the downward movement of the free end of the armature bar 16. The result of this variation in the magnetic circuit is the production of a flow of current in the electric circuit through the coil 29 and the sparking contacts 30 and 32. With this low tension

type of machine the downward movement of the armature bar 16 and the mechanical opening of the contacts bears a timed relation such that the breaking of the electric circuit by these contacts will occur at a time when the current flowing through the electric circuit is at or near a maximum and consequently a full spark will be obtained between these contacts for the purpose of exploding the fuel charge in the cylinder 31.

In order to provide an additional path for the lines of force between the poles of the magneto 10 at the time the armature 15 is moved away from its normal position, I provide an auxiliary armature, or keeper, 40 which is positioned near the polar extremities of the magnet 10. This auxiliary armature is secured to a portion of the guide member 21 by a leaf spring 41. The latter is riveted to the end of the armature 40 as indicated at 42 and is secured to the member 21 by any suitable means, as by the screws 43. The auxiliary armature 40 is composed of soft iron or other magnetic material and the spring 41 may be composed of either magnetic or non-magnetic material. The spring 40 is very light as it need perform no function other than support the armature but it may also serve to press the free end of the armature 40 toward the adjacent portion of the magnet 10. The armature is, of course, drawn by the magnet 10 and this pull is sufficient to draw it into engagement with the magnet irrespective of the tension of the spring 41. The free end of armature 40 is normally stopped by an arm 44 which is pivoted at 45 to the outer face of the guide member 20. The arm 44 is provided with a projection 46 which lies in the path of movement of the armature bar 16 and bears against the latter when it is in attracted position. Normally the attraction of the main armature 15 is such as to force the arm 44 outward against the auxiliary armature 40 and hold it away from the magnet 10. However, as the main armature bar 16 descends, the projection 46 on the arm 44 descends and said arm rotates about its pivot 45 by reason of the magnetic pull exerted upon the auxiliary armature 40, and the free end of the latter finally comes into engagement with the magnet 10. In this way a shunt for the lines of force of the magnetic circuit is provided.

The purpose of the auxiliary keeper 40, is to assist in maintaining the magnetism of the magnet 10. This auxiliary keeper may not be necessary in all cases and where not needed said armature and the associated arm 44 may be omitted. A stop 44^a limits the movement of arm 44 in one direction and armature 40 restrains its movement in the other.

In order to more securely hold the magnet 10 in position upon the base 11 and to prevent its being moved under the repeated

blows of the armature 15, the base 11 is provided with an up-turned projection 47 which engages the curved portion of the magnet 10. This projection may not be necessary

5 in all instances but it will obviously assist where only a single bolt 12 and bar 13 are used to hold the magnet 10 upon the base.

Referring now to the high tension magneto illustrated in Figs. 5 to 9 inclusive, it 10 will be seen that the construction and arrangement of the parts is the same in this form of the invention as in the preceding, with certain exceptions. In the high tension machine the coil upon the armature 15, designated 15 50, includes a primary winding 51 and a secondary winding 52. This coil, like the coil 49, is positioned between the blocks 17 and 18 of the armature structure. In this form of the invention, these blocks 17 and 20 18 are secured in place by pins 53 and 54 which have a driving fit in holes through the blocks and the bar 16. The high tension machine is also provided with a condenser 55 which is preferably secured to the base 11 25 by screws 56. It is also preferably located between the arms of the magnet 10. In this form of the invention, the armature 15 and the adjacent guide member 20 carry electrical contacts 57 and 58. The contact 57 ex-

30 tends through a block 59 which is secured to the side of the member 20 by screws 60. This contact is suitably insulated from the block 59 by passing through a sleeve 61 of insulating material which separates it from the block 59. Locking nuts 62 and 63 serve to hold the contact firmly in place. Electrical contact may be made by attaching the conducting wire to the upper end of the contact 57. This may be done by soldering the wire 40 to the end of the contact or by gripping it between the head 64 and the adjacent nut 65.

The contact 58 is in the form of a plunger located in a socket 65^a in the armature bar 16. This contact has a reduced stem 66 45 which passes through an opening in the plate 67 secured to the under side of the bar 16 in any suitable way, as by screws, one of which, designated 68, is shown. A coiled compression spring 69 surrounds the stem 66 and 50 bears against the plate 67 at one end and against a collar 66^a on the contact 58 at the other end. The action of this spring is to normally push the contact 58 upward. By this means a yielding electrical connection 55 is established between the contacts 57 and 58 and the two are maintained in contact during the initial movement of the armature 15 away from magnet 10. As the armature 15 moves downward, however, a point is 60 reached at which the contacts 57 and 58 separate. This point is determined by the engagement of the collar 66^a with a flange 67^a formed at the upper end of the socket 65^a in which contact 58 reciprocates. The closed 65 position of all the parts is shown in full lines

in Figs. 5 and 6 and the open position in dotted lines in Fig. 6 and in full lines in Fig. 7.

In this high tension machine the contacts 57 and 58 are ordinarily included in circuit 70 with the primary winding 51 of the coil 50. This is diagrammatically illustrated in Fig. 9. As there shown the circuit is completed by grounding the armature 15 and one terminal of the winding 51. The secondary winding 75 52 is connected in circuit with the condenser 55 and the sparking contacts 70 and 71. These contacts, like contacts 30 and 32, are located in the engine cylinder but unlike them are separated by a permanent air gap which 80 the high tension of the secondary circuit overcomes and thus produces a spark. This action, of course, occurs when the armature 15 has been moved down by oscillating member 24 and the contacts 57 and 58 separated 85 to break the primary circuit. Obviously, the circuit connection might be varied by connecting the condenser 55 in series or in parallel with the spark terminals 70 and 71. Thus if switch 72 is left open and switch 73 90 is closed on its upper contact, the condenser will be connected in series. On the other hand, if switch 72 is closed and switch 73 is closed on its lower contact, the condenser will be connected in parallel. 95

In this form of the invention the keeper, or auxiliary armature, 40 might also be dispensed with if desired, the same as in the low tension machine, heretofore described. Likewise, the yoke 26 and spring 25 might 100 be omitted. Again, the pivot pin 23 might be left out. All of these modifications and others not disclosed herein will be apparent to persons skilled in this art.

It may also be pointed out that in the low tension machine the timed relation between the initial movement of the bar 16 and the separation of the contacts is brought about by a yielding connection between two sections of the rod 33. These sections are connected by a telescopic joint having an enclosing sleeve 74 and an expanding spring 75. Normally the parts are extended as shown in Fig. 4. When so extended, a collar on the upper section engages a flange at the upper 110 end of sleeve 74. When bar 16 first engages rod 33 in its downward movement, the upper section of the latter is moved downward and spring 75 is compressed. When the applied pressure overcomes the resistance of spring 115 34, then the lower section begins its downward movement. This continues until bar 16 has reached the limit of its downward movement. Upon the return of bar 16, rod 33 and its parts return to normal. 120

What I claim as new and desire to secure by Letters Patent of the United States, is:

1. A magneto comprising a magnet, a main oscillating bar armature extending between the poles of said magnet, means for 130

4
actuating one end of said main armature to move it about its other end as a pivot, an electric coil mounted on said armature and having windings adapted for inclusion in an ignition circuit, an auxiliary bar armature yieldingly secured to one pole of said magnet, and means cooperating between said main and auxiliary armatures to permit the free end of said auxiliary armature to approach the adjacent pole of said magnet as said main armature is moved away from its normal position.

2. A magneto comprising a magnet, a main oscillating bar armature extending between the poles of said magnet, means for actuating said main armature about a pivotal axis, an electric coil positioned in the magnetic field of said magnet and having windings adapted for inclusion in an ignition circuit, an auxiliary bar armature for said magnet, and means cooperating between said main and auxiliary armatures to permit said auxiliary armature to approach said magnet as said main armature is moved away from said magnet.

3. A magneto comprising a magnet having a polar face, a main oscillating armature having a face adapted to fit against said polar face, means for moving said armature about a pivotal axis to move said armature face toward and from said polar face in a

direction approximately normal to said latter face, an electric coil positioned in the field of said magnet and having windings adapted for inclusion in an ignition circuit, an auxiliary armature for said magnet, and means whereby one armature recedes from said magnet as the other approaches it.

4. A magneto comprising a magnet, a main oscillating armature, an auxiliary armature, said armatures having their oscillating movements in different planes, means acting between said armatures whereby the movement of one of said armatures is dependent upon the movement of the other, and an electric coil positioned in the field of said magnet and having windings adapted for inclusion in an ignition circuit.

5. A magneto comprising a magnet, pivotally mounted main and auxiliary armatures, and a pivotally mounted stop device for holding said auxiliary armature away from said magnet except when said main armature has receded from said magnet, and an electric coil positioned in the field of said magnet and having windings adapted for inclusion in an ignition circuit.

In testimony whereof, I hereunto subscribe my name this 6th day of January, A. D. 1919.

ALEXANDER H. HYNDMAN.
